Specification for Design.

Patented Oct. 5, 1920.

Application filed November 13, 1919. Serial No. 337,861. Term of patent 14 years.

To all whom it may concern:

Be it known that I, RALPH E. THOMPSON, a citizen of the United States, residing at Brookline, in the county of Norfolk and State of Massachusetts, have invented a new, original, and ornamental Design for Safety-Razor Cases, of which the following is a specification, reference being had to the

accompanying drawing, forming a part thereof.

The figure is a perspective view of a safety razor case showing my new design.

I claim:

The ornamental design for a safety razor case as shown.

RALPH E. THOMPSON.
